PICKER STICK CHECK FOR LOOMS

Joseph J. Hemingway, Paxton, Mass., assignor to
Crompton & Knowles Loom Works, Worcester,
Mass., a corporation of Massachusetts

Application April 17, 1946, Serial No. 662,819

6 Claims. (Cl. 139—169)

1

This invention relates to improvements in picker stick checks for looms and it is the general object of the invention to provide a check which will apply a varying checking force to a picker stick in such manner that forces acting on the shuttle at the end of the checking operation will not tend to cause shuttle rebounding.

It is desirable that the shuttle come to rest in the shuttle box in proper position for its next picking operation and this is additionally true in weft replenishing looms in which the shuttle must be correctly placed to receive the incoming bobbin. Various forms of checking devices have been employed, some of them acting directly on the shuttle, and others acting on the picker stick. Picker checks which have been used heretofore have been so constructed that they check the blow of the shuttle against the stick in such manner that shuttle rebound results and the misplaced shuttle is not correctly positioned for picking or bobbin transfer.

It is an important object of my present invention to provide a form of shuttle check in which a stick engaging strap extends across a weighted member mounted for pivotal movement on the lay, but acting in such manner that its response to motion of the stick is delayed, thereby permitting a deformation of the strap to vary the checking force exerted by the strap. The strap is deformed by the stick in such a direction that the checking force increases immediately after impact by the stick and before the weighted member is able to move. Thereafter, the weighted member moves in response to deformation of the strap and in doing reduces the force acting on the stick tending to unseat the shuttle or cause rebounding of it.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a rear elevation of the replenishing end of the loom having my improved form of picker stick check applied thereto.

Fig. 2 is an enlarged rear elevation of the check shown in Fig. 1.

Fig. 3 is a section on line 3—3 of Fig. 2 showing the check in two different positions.

Fig. 4 is a section taken on line 4—4 of Fig. 2 along the axis around which the check swings.

Fig. 5 is a detail plan view looking in the direction of arrow 5, Fig. 2, the brace which connects the check to the lay being shown in section, and

2

Fig. 6 is a diagrammatic view illustrating the changing values of the checking forces during operation of the picker check.

Referring particularly to Fig. 1, I have shown a loom frame 10 having in the lower part thereof a rocker shaft 11 supporting the lay swords one of which is indicated at 12. The lay 13 has a shuttle box 14 and in the present instance is provided with a picker spindle 15 along which slides a picker 16 propelled by a picker stick 17. The latter is pivoted at 18 to a rocker iron 19 secured to the rocker shaft 11, and a light tension spring 20 is connected to the picker stick and to a collar 21 secured to the rocker shaft 11 for the purpose of moving with picker stick toward its outward position upon completion of a picker stroke.

The bottom shaft 25 of the loom is provided with a picking arm 26 which periodically engages a picking cam 27 on the picker shaft 28. A picker arm 29 extending upwardly from shaft 28 is attached to a sweep stick 30 carrying a lug strap 31 which surrounds the picker stick 17.

The shuttle S is picked back and forth across the loom and when leaving the box 14 is pushed by the picker 16 as the latter is moved inwardly or toward the right as viewed in Fig. 1 by operation of the picking mechanism. After the picking arm 26 leaves the cam 27 spring 20 contracts to move the picker stick 17 to the left, Fig. 1, to the picker stick check to be described. When the shuttle returns to box 14 the stick is moved outwardly an additional amount as will be set forth in greater detail hereinafter.

Since the invention is particularly useful in weft replenishing looms I have indicated in dotted lines a bobbin B to be inserted into the shuttle S by a transerrer arm 32 whenever replenishment is called for and the shuttle is in box 14. It will be obvious from the upper part of Fig. 1 that the shuttle should be correctly placed to receive the bobbin B, but it will not be so placed if for any reason that shuttle should rebound in a direction toward the center of the loom, or toward the right as viewed in Fig. 1. The lay has at the left end thereof as seen in Fig. 1 a lay end 33 provided with a smooth vertical surface 34, see Fig. 3, against which the picker stick can slide during the latter part of the boxing of the shuttle.

Except as pointed out hereinafter the matter thus far described is of common construction and operates in the usual manner. The shuttle box may be provided with a binder or other form of shuttle check not shown which will absorb the

greater part of the energy stored in the shuttle as it enters box 14, but there will nevertheless be sufficient residual energy in the shuttle to cause it to exert considerable outward force on the picker 16 and picker stick 17.

In carrying my invention into effect I secure to the lay a depending bracket 35 having a friction shell 36 from which extends laterally a bearing web 37. The picker check includes a weighted pivoted member or check arm 38, a strap 39 made conveniently of leather or similar flexible friction material, and a spring 40. The check arm 38 has spaced top and bottom bearings 41 and 42, respectively, and has a wall 43 the outer end of which remote from the bearings 41 and 42 is curved as at 44.

A screw 45 extends downwardly through a collar 46 inclosed within the upper bearing 41 and also extends through the web 37 and through a sleeve 47. The lower end of screw 45 is screw threaded into a clamped support member 48 having a head 49 on which the bearing 42 rests and a cylindrical body 50 extending through bearing 42. When the screw 45 is tightened it clamps the member or fitting 48 against the sleeve or collar 47 and holds the latter firmly against the web 37. When the screw 45 is in its correctly set position the bushing 46 permits free angular movement of the check arm 38.

A shell 55 extending along the cylindrical body 50 is surrounded by the lower part of the spring 40 and has formed integral therewith an upwardly extending arm 56 spaced from the body and against which the lower end 57 of the spring bears. The shell rests on bearing 42 and its upper end is slightly below sleeve 47. The upper end of the spring extends as at 58 into the sleeve 47 which is held clamped in adjusted angular position by screw 45. It is by this construction that the spring tends to turn the shell 55 in a clockwise direction as viewed in Fig. 3.

The strap 39 has its outer end secured as at 60 to the curved end 44 of wall 43 and has its inner end secured as at 61 to the upwardly extending arm 56. The spring normally holds this strap taut and extending from the end of wall 43 to a point of tangency with friction shell 36. The spring thus holds the straight part of the strap spaced from wall 43 and tends to move the latter in the clockwise direction as viewed in Fig. 3. Motion in this direction is limited by engagement of a stop finger 63 on the upper bearing 41 with bracket 35, see Fig. 5.

The parts are so set that the normally straight part of the strap will always be inclined toward the path of the picker stick and in the direction in which the stick is moved by the shuttle. The shuttle will occupy the full line position shown in Fig. 3 at the beginning of a picking stroke of the picker stick, and spring 40 will be under a stress tending to move the check toward the stick. Under these conditions also the stop finger 63 will be spaced from the bracket as shown in full lines, Fig. 5. As the stick moves on its working stroke from the right of the position shown in Fig. 1 the spring will move the check to the dotted line position of Fig. 3, and stop finger 63 will engage bracket 35, see dotted lines, Fig. 5. After the working stroke has been completed the spring 20 will return the stick but will not be able to move it to its outermost position due to engagement of the stick with the strap. The stick will stop about as indicated in dotted lines in Fig. 3 with its outer rear edge in engagement with the strap and the latter will be straight, 75

but inclined in the direction in which the picker stick will be moved by the shuttle. When the shuttle returns it will strike the picker 16 and in turn move the stick 17 to its extreme outward position in a very brief interval of time and cause a succession of force reactions as indicated diagrammatically in Fig. 6.

When the stick starts to move toward its outermost position from the dotted line position of Fig. 3 it will be in contact with the straight part of the strap 39 at a point, such as a, Fig. 6, and the force of the stick against the strap will be perpendicular to the latter and in a direction indicated by line b. The base of the triangle of this force indicated at a-c, Fig. 6, represents the reaction force tending to stop onward movement of the stick at the instant of impact with the straight strap due to movement of the shuttle. As the stick moves quickly to its outermost position the strap will be deformed as indicated in dotted lines in Fig. 6 before the weighted arm 38 due to its inertia can move. Under these conditions the resultant of the longitudinal and lateral forces acting on the stick will be as indicated by the dotted line d, this line approximately dividing the angle formed in the strap and suggested by the dotted line. The base e-f of the corresponding triangle is considerably longer than is line a-c, indicating that the resisting force has increased. By the time the stick has reached a position corresponding to e the arm 38 will have started to swing in a counter-clockwise direction around the screw 45 and will ultimately come to rest in the dot and dash line position of Fig. 6, in which the straight part of the strap passes through point e. The resultant of forces under this last named condition is indicated by line g forming a triangle the base of which, indicated at e-h, is much smaller than the bases of either of the other two triangles. This indicates that the longitudinal force tending to move the shuttle out of the box is much less when the stick is in its outermost position than it is at the beginning of the checking operation. It will also be seen that this reduction in checking force is preceded by a condition in which the force is greater than that existing at the start of the checking operation.

The triangles indicated in Fig. 6 suggest that a considerable lateral force is brought to bear on the stick which holds it against the flat surface 34 shown in Fig. 3, resulting in frictional dissipation of some of the energy of the shuttle. This lateral force also undergoes variation as the picker stick slides along the strap due to changing stresses in the spring 40. Thus, the full line triangle in Fig. 6 corresponds to a condition in which the spring is under least torsional strain and the resultant b will consequently be of minimum value. When the strap assumes the dotted line position of Fig. 6 there is an increase in strap length between the arm 43 and the point of tangency with the shell 36 which is accompanied by movement of arm 56 and increases torsional strain in spring 40. This increased spring strain causes the resultant force d to be somewhat longer than the resultant b. When the check finally comes to rest that part of the strap engaging the stick is again straight and there is a slight pull-back on the strap accompanied by a lessening of the torsional strain of the spring. Due, however, to the angular movement of the arm 43 the spring is likely to be under slightly more strain than is represented by the resultant b, and it is for this reason that the line g is

drawn in Fig. 6 longer than line *b*, but shorter than line *d*.

There is therefore an increase in the lateral force as well as the horizontal force during an intermediate stage in the checking operation. When the shuttle is picked out of its box, however, there is no bending of the straight part of the strap and it is not necessary for the stick to overcome an increased force during the first part of the picking stroke as would be the case if the checking forces came into play in reverse order at such time.

From the foregoing it will be seen that I have provided a simple form of picker stick check comprising a strap inclined toward the path of the picker stick and in the direction in which it is moved by the shuttle and normally held taut between two points so that the strap can bend between these two points before its weighted carrier due to its inertia can move appreciably. Due to operation of the strap and arm 38 the force at the instant of impact steadily increases during deformation of the strap and then diminishes as the check arm 38 due to delayed response to forces acting on it reaches the full line position shown for instance in Fig. 3. This decrease of force very materially reduces any tendency which the picker stick check has tending to cause rebounding or unseating of the shuttle in the box 14.

Having thus described my invention it will be seen that changes and modifications may be made therein by those skilled in the art without departing from the spirit and scope of the invention and I do not wish to be limited to the details herein disclosed, but what I claim is:

1. In a picker stick check for a loom having a lay and a picker stick moved in a given path along the lay by a shuttle, a flexible strap normally inclined toward said path and in the direction in which the picker stick is moved by the shuttle at a given acute angle, a pivot supported by the lay, resilient means around said pivot, and an arm movable angularly on said pivot, one end of the strap being connected to the end of the arm remote from the pivot and the other end of the strap being connected to said resilient means, said stick normally engaging said strap and upon boxing of the shuttle causing bending of the strap relatively to said arm and the latter thereafter moving angularly about said pivot to cause said strap to be disposed at an acute angle to said path less than said given acute angle.

2. In a picker stick check for a loom having a lay and a picker stick moved in a given path along the lay by a shuttle, a pivot supported in fixed position on the lay, an arm swingable about said pivot, resilient means surrounding said pivot, a friction shell fixed with respect to said pivot and spaced therefrom, and a flexible strap secured to said resilient means and extending around said friction arm and connected to that end of the arm remote from the pivot, said strap being normally spaced from the arm and inclined at an acute angle to said path and toward said path in the direction in which the picker stick is moved along said path by the shuttle, the latter normally engaging said strap and upon movement thereof by the shuttle deflecting said strap relatively to said arm and the picker stick thereafter moving angularly about said pivot and causing the strap to be disposed relatively to said path at an acute angle less than the normal acute angle at which the strap is disposed to said path.

3. In a picker stick check for a loom having a lay and a picker stick moved in a given path along the lay by a shuttle, a pivot fixed with respect to the lay, a friction shell fixed with respect to the lay and spaced from the pivot, a resilient means surrounding said pivot, an arm mounted for movement on and about said pivot and having the end thereof remote from the pivot curved toward said path, and a flexible strap secured to said end of the arm and extending around said shell and attached to said resilient means, said resilient means normally holding the strap straight between said shell and said curved end of the arm and inclined toward said path and in the direction in which the picker stick is moved by the shuttle at a given acute angle, the stick normally engaging said straight part of the strap and being moved therealong by the shuttle when the latter is boxed and causing deflection of the strap toward said arm, said arm thereafter moving angularly around said pivot to cause that part of the strap between the shell and the curved end of the arm to be again straight but disposed at an acute angle relatively to said path less than said given acute angle.

4. In a picker stick check for a loom having a lay and a picker stick moved in a given path along the lay by a shuttle, a weighted member pivotally mounted with respect to the lay, resilient means supported by the lay, a flexible strap connected to said weighted member and said resilient means and having a part thereof normally straight and spaced from said weighted member by said resilient means, and stop means normally holding said weighted member and strap in such position that the straight part of said strap is inclined at a given acute angle to said path toward the latter and in the direction in which the picker stick is moved along said path by the shuttle, the picker stick being moved along said strap by a force derived from the shuttle and causing deflection of the strap toward said weighted member and the latter thereafter moving angularly about said pivot and cooperating with the resilient means to cause that part of the strap engaging the picker stick to be straight but disposed relatively to said path at an acute angle less than said given acute angle.

5. In a picker stick check for a loom having a lay and a picker stick moved in a given path and direction along the lay by a shuttle, a pivot fixed with respect to the lay, a weighted arm movable angularly about said pivot, resilient means supported by the lay, and a flexible strap connected at one end thereof to said resilient means and at the other end thereof to that part of the arm remote from said pivot, said strap normally being spaced from the arm and having that part thereof engaging the stick held straight by said resilient means and inclined at a given acute angle to said path toward the latter and in the direction in which the picker stick is moved by the shuttle, said strap and said arm cooperating during movement of the picker stick along said strap by a force derived from the shuttle to cause deflection of the strap in such manner as to increase the reaction force of the strap on said stick in a direction along said path opposite to the direction in which the stick is moved by the shuttle, and said arm thereafter moving angularly about said pivot and causing the strap to assume a position relatively to said path at an acute angle less than said given acute angle, whereby the reaction force exerted by said strap on said stick along said path

is less than the reaction force existing when said strap was deflected.

6. In a picker stick check for a loom having a lay and a picker stick moved in a given path along the lay by a shuttle, a flexible picker stick checking strap, and means tending to hold said strap taut and normally maintaining a part thereof straight and inclined at a given acute angle to said path toward the latter and in the direction in which the picker stick is moved along said path by the shuttle, said means including a resilient member connected to one end of the strap and a weighted arm connected to the other end of the strap and pivotally mounted with respect to the lay and having a part thereof spaced from said strap, the picker stick when moved along said path deflecting said strap toward said part of the weighted arm before the latter can move pivotally due to the inertia thereof, said weighted arm

thereafter moving pivotally away from said path due to the tendency of said means to hold said strap taut and said part of the strap thereupon becoming straight but at an acute angle to said path less than said given acute angle.
